UNITED STATES PATENT OFFICE.

EMIL GOTTSCHALCK, OF TREPTOW, NEAR BERLIN, LOTHAR WERNER, OF BERLIN, AND AUGUST GAST, OF STEGLITZ, GERMANY, ASSIGNEES TO THE FIRM OF CHEMISCHE FABRIK GRIESHEIM-ELEKTRON, OF FRANKFORT-ON-THE-MAIN, GERMANY.

ELECTRIC SAFETY-LAMP.

1,076,495.

Specification of Letters Patent. Patented Oct. 21, 1913.

Application filed December 7, 1912. Serial No. 735,477.

To all whom it may concern:

Be it known that we, EMIL GOTTSCHALCK, a resident of Treptow, near Berlin, LOTHAR WERNER, a resident of Berlin, and AUGUST GAST, a resident of Steglitz, near Berlin, Germany, citizens of Germany, have invented certain new and useful Improvements in Electric Safety-Lamps, of which the following is a specification.

10 Our invention relates to an electric lamp which can be made in portable form or as a stationary lamp and which is so constructed that it can be used without danger in mines, in various industrial factories, and so on 15 where combustible gases may exist. In such cases, as is well known, care must be taken that the gases are not ignited by sparks, whether through actions in contravention of regulations, through accidents to the lamps, 20 or through malicious dealings.

The subject of the invention belongs to a class of lamps, of which several types are already known, in which means are provided for safeguarding against explosion 25 and preventing unauthorized access to the interior of the lamp. Such means commonly include a device for interrupting the current on the breakage or removal of the globe, or on the lamp being taken out, one terminal of the source of current being joined to a contact in the interior of the casing and the other to the lamp socket.

According to the invention a metal member is provided between the contact in the 35 casing and the end contact of the lamp, normally joining these contacts but not directly connected to the source of current. Upon the safety device operating this member is jerked forward by a spring and is locked 40 in the forward position. It is then impossible to press it again into contact with the contact in the casing and moreover it makes this contact inaccessible.

Three forms of construction are illustrated 45 in the accompanying drawings. The first form is shown in elevation in Figure 1, and in cross section on line I—I of Fig. 1 in Fig. 2. Fig. 3 is a cross section of a second form. Figs. 4 and 5 are sections on the line 50 II—II of Fig. 3, Fig. 4 being a view looking toward the point of the incandescent lamp, and Fig. 5 a view looking from the point of the lamp. Fig. 6 shows a third form of construction also in cross section.

Before the details of the different forms 55 of construction are referred to, those parts may be described which are the same in all the constructions.

The lamp is supposed in all the examples to be portable and has a metal casing A. 60 This contains a source of current which may for example be two series connected voltaic cells B or a secondary battery. One pole of the source of current is joined to the contact C which is mounted in the interior of 65 the casing but insulated therefrom. The other pole of the source is connected to the metal casing A through a fuse D. One wall of this casing, for example the front wall, has a circular opening in the middle of 70 which the insulated contact C is arranged and which is surrounded by a circular flange E. In this flange engages a ring F having two pins F' which engage in a circumferential slot on the inner surface of the flange 75 E. Branching from this circumferential slot are two slots parallel to the axis of the opening extending to the front edge of the flange which allow the insertion and removal of the ring F with its pins F'. In 80 this way the ring F is secured in the flange E by a so-called bayonet joint which, however, may be replaced by any other suitable connection. Over the edge F² of the ring 85 F engages a covering ring G which in its turn—as is disclosed in the U. S. A. Patents Nos. 1,022,072 and 1,022,073, both of Apr. 2, 1912, and No. 1,025,394 of May 7, 1912, all granted to Gottschalck—forms a bayonet 90 connection with projections A¹ on the casing A. The covering ring G is so formed and arranged—also in known manner—that it can only be removed after the casing is opened. Thus the insertion or removal of the ring F and of the parts secured to it 95 and supported by it are only possible after removal of the covering ring G. The ring F holds the globe H within which is the incandescent lamp I. The socket of the lamp is provided with a screw thread I¹ and 100 an end contact I² insulated from the socket. One end of the filament I³ of the lamp is connected to the screw threaded socket I¹ and the other to the end contact I².

In the first form of construction (Fig. 2) 105 the screw threaded socket I¹ of the incandescent lamp is inserted in a metal casing J fastened to the insulating disk K. This lat-

ter carries also a reflector L which is conductively connected with the casing J together with a cap M which must be insulated from the casing J. There is also 5 secured upon the insulating disk K a thin metal disk N having springy lugs N¹ which must be conductively connected to the casing J. The cap M covers the socket of the incandescent lamp and normally, *i. e.* in the 10 position shown, forms a conductive connection between the contact C in the interior of the casing and the end contact I² of the incandescent lamp I. Between the edge of the cap M or the insulating disk K and an insulating plate O which covers the opening 15 in the casing within the circular flange E is arranged a spring P. There is a central opening in the plate O for the passage of the closed end of the cap M. The interior 20 of the ring F has a screw thread on a part of its length and in this is inserted a ring Q. Between this latter and the flange of the globe H is introduced a ring Q¹ of soft rubber. The interior of ring Q is smooth 25 near the insulating disk O but at the other end is provided with notches Q². The projections N¹ of the metal disk N rest against the inner surface of the ring Q. The reflector L abuts against the shoulder H¹ on 30 the globe H.

The construction described operates in the following manner: Normally all the parts are in the position shown in Fig. 2. The current from the source B therefore takes 35 the following path: battery B, fuse D, casing A, flange E, ring F, ring Q, projections N¹, disk N, casing J, screw thread I¹, filament I², end contact I², cap M, contact C, battery B. If the globe H receives a jar 40 or blow which may be dangerous to the incandescent lamp I it breaks off at the shoulder H¹. Since the reflector L is then no longer held back by the shoulder H¹ the compressed spring P can expand. By pressure on the disk K it moves the springy projections N¹ of disk N so far forward upon 45 the inner surface of ring Q that they engage in its notches while it also thrusts forward the incandescent lamp I and the cap M so that the conductive connection between cap M and contact C is broken. It 50 is now impossible in consequence of the engagement of the springy projections N¹ of the disk N in the notches of ring Q to move 55 the members back into the position shown so as to close the circuit again. It is equally impossible to close the circuit by rotating the incandescent lamp I for if it is screwed down after the breaking of the globe H it 60 never reaches contact C.

By making the shoulder H¹ in the globe H sufficiently broad it is possible to insure that the globe shall be broken by any shock or blow which could endanger the incandes-

cent lamp I. But then the globe H would 65 be itself too delicate that is to say, it would be shattered by a shock or blow not strong enough to injure the incandescent lamp. In other words with the form of construction 70 according to Fig. 1 a good many globes are required.

In the construction according to Figs. 3 to 5 the problem in question is solved in a somewhat different manner. In this case the globe H itself is brought into the circuit 75 and for this purpose is provided with a ribbon like metal lining H² which may be produced by burning, by electro-deposition or otherwise. The lining H² in the first place completely covers the outer side of the flange 80 H⁴ and the inner side of a notch H³ yet to be described. From the latter it is carried up a little way on the inner side of the globe toward its rounded portion, then forms a nearly closed ring and from this is continued to the inner side of the flange H⁴ and there also forms a nearly closed ring 85 (Fig. 4). The inner side of flange H⁴ with its metal coating H² bears on the turned over projections R¹ upon a ring R (Fig. 3) 90 which is secured to one of two insulating disks K and is connected with the casing J. The reflector L is mounted and insulated upon the front side of the outer insulating plate K and surrounds the incandescent 95 lamp I to a certain height. In the notch H³ of the globe H is a pin F² which is inserted in ring F and engages also in a corresponding notch in the insulating plates K. Thus the various parts can only be put together in one particular relative position of 100 the insulating disks K with the members secured to them and of the globe H. The purpose of thus fixing the mutual position is that the current passing from the ring F to the metal lining H² on the outer side of the flange H⁴ must pass through the whole length of the lining H² before it reaches the projections R¹ upon the ring R. Normally the current takes the following path: Battery 105 B, fuse D, casing A, ring F, metal lining H² of the globe H, through all its length, projections R¹, metal ring R, casing J and from here by the same path as in the first construction. If the globe H is broken 110 by a jar or blow, the continuity of the lining H² is broken and so the current is interrupted. Should it happen that the incandescent lamp I has received no damage, an attempt might be made to put current 115 through it again by introducing a wire through a hole or gap in the shattered globe H putting one end of it on the casing A or the ring F and the other on the casing J. That, however, is prevented by the special formation of the reflector L. This makes the casing J or the screw thread I¹ accessible 120 only on the removal of the incandescent 125

lamp I. Such removal, however, breaks the contact between the end contact I² and the cap M and it is therefore impossible by these means to get current through the incandescent lamp. Now it might occur to some one to prevent breaking of the contact between end contact I² and the cap M by screwing out the incandescent lamp and inserting a small piece of metal in the cap M. Even then, however, it is not possible to get current to pass on re-inserting the lamp I, for the piece of metal would either immediately short-circuit between the cap M and the casing J which is specially lengthened for this purpose so that fuse D would blow, or such short-circuit would be produced on the screwing in of the incandescent lamp since its conical end would press the piece of metal to one side so as to bring it against the casing J. After the lamp I is screwed out it is certainly possible to establish connection *e. g.* through a wire between the casing A or the ring F on the one hand and the cap M or the contact C on the other hand. That, however, would short-circuit the source of current and immediately blow the fuse D in the interior of the casing so that no spark could be produced outside which might ignite combustible gas. Finally, if after the globe H has been broken the fragments of its flange H² are removed which may yet be within the ring F, the spring P expands and presses out the insulating plate K with the members secured upon it and the springy projections N¹ and disk N engage in the notches of ring Q as described in connection with the first form of construction.

The third form of construction (Fig. 6) differs from the second in the fact that the spring P here presses only on a special insulating disk C which carries the cap M to which is secured the disk N with its springy projections N¹. All the remaining parts in this construction are fixed. In this case the spring P expands if the incandescent lamp I is merely screwed out. If this is done the disk N moves forward and its projections N¹ engage in the notches of the ring Q. It is therefore impossible after the lamp has been screwed out to press back the cap M far enough to permit it coming in contact with contact C. Finally in the form of construction according to Fig. 6 the ring Q is provided with a flange Q² upon which the spring P abuts. This arrangement, which may be adopted in the other constructions, has the purpose of enabling all the parts to be removed or replaced simultaneously with the ring F.

The invention is not restricted to lamps of the type described in the introduction. For example the rings F, G may be secured in other manner than that illustrated.

Having now particularly described and ascertained the nature of our said invention and in what manner the same is to be performed, we declare that what we claim is:

1. In an electric safety lamp, the combination of a casing, a source of current therein, a fixed contact within said casing and joined to one pole of said source of current, a metal ring to receive a lamp and joined to the other pole of said source of current, a movable metal member within said ring and normally touching said contact, a lamp having two terminals, one terminal being in contact with said ring and the other with said metal member, means tending to press said member out of connecting position, and means adapted to lock said member, when brought out of connecting position. 70

2. In an electric safety lamp, the combination of a casing, a source of current therein, a fixed contact within said casing and joined to one pole of said source of current, a metal ring to receive a lamp and joined to the other pole of said source of current, a movable metal member within said ring and normally touching said contact, a lamp having a circumferential and an end contact, the former being in contact with said ring and the latter with said metal member, means tending to press said member out of connecting position, and means adapted to lock said member, when brought out of connecting position. 85

3. In an electric safety lamp the combination with a casing of a source of current therein, a contact joined to said source of current, a lamp mounted in said casing, a terminal thereon, a metal member interposed between said terminal and said contact and normally joining the same, means tending to press forward said metal member 100 so as to break contact, means for locking said member when thus pressed forward, and a lamp globe surrounding said lamp and normally retaining said metal member in position to establish contact. 105

4. In an electric safety lamp, the combination of a casing, a source of current therein, a fixed contact within said casing and joined to one pole of said source of current, a metal ring to receive a lamp and joined to the other pole of said source of current a movable metal member within said ring and normally touching said contact, a lamp having two terminals, one terminal being in contact with said ring and the other with said metal member, means tending to press said member out of connecting position, means adapted to lock said member, when brought out of connecting position, a globe covering the lamp and independent means for breaking the lamp circuit upon rupture of the globe. 115

5. In an electric safety lamp the combi-

nation of a casing containing a source of current, a mounting to receive a lamp, a contact on said casing within said mounting, a metal cap covering said contact and 5 normally contacting with it, means for pressing forward said cap when free and means for locking the cap when so pressed forward.

6. An electric safety lamp comprising a 10 casing, a source of current therein, a mounting for a lamp notched on its interior, a contact within said mounting, a cap covering said contact, spring projections attached to said cap adapted to engage the 15 notches of the mounting, and a spring normally tending to press said cap forward.

7. In an electric safety lamp, the combination of a casing containing a source of current, a boss thereon, a ring, a removable 20 fastening securing said ring in said boss, a lamp mounting supported in said ring, a notched member supported in said ring, a contact within said boss, a cap covering said contact, springy arms attached to said 25 cap adapted to engage said notches and means tending to press forward said cap.

8. In an electric safety lamp, the combination of a casing containing a source of current, a boss thereon, a ring, a removable 30 fastening securing said ring in said boss, a lamp mounting supported in said ring, a globe covering said mounting and supported in said ring, a notched member supported in said ring, a contact within said boss, a 35 cap covering said contact, springy arms attached to said cap adapted to engage said notches and means tending to press forward said cap.

9. In an electric safety lamp, a casing, a 40 boss on said casing, a contact within said boss, a notched member within said boss, a disk having springy projections adapted to engage said notches, a lamp mounting at

tached to said casing, a metal cap interposed between said lamp mounting and said contact, a globe having a shoulder around said mounting, a reflector attached to said mounting and abutting upon said shoulder, and means for pressing forward said cap, disk and mounting so as to press said reflector upon said shoulder.

10. An electric safety lamp comprising a 45 casing, a source of current therein, a boss upon said casing, a notched member within said boss connected to one pole of said source, a contact within said boss connected to the opposite pole, said source of current being insulated from said casing, a cap covering said contact, a disk supporting a lamp socket and carrying springy projections adapted to engage said notched member, and means tending to press forward said cap and said disk.

11. An electric safety lamp comprising a 55 casing, a source of current therein, a contact joined to one pole of said source, a cap covering and normally touching said contact, means normally pressing forward said cap and means for locking said cap when pressed forward, a globe normally preventing said forward movement, a lamp socket within said globe, a metallic ribbon upon said globe, and connections between said lamp socket, metallic ribbon and the other 60 pole of the source.

In witness whereof, we have hereunto signed our names this 25 day of Nov. 1912, in the presence of two subscribing witnesses.
